Primary Examiner — Calvin E Vansant*Assistant Examiner* — Benjamin L. Gray(74) *Attorney, Agent, or Firm* — Andrus Intellectual Property Law, LLP(57) **CLAIM**

The ornamental design for an electric machine as shown and described.

DESCRIPTION

FIG. 1 is a front view of an electric machine;
FIG. 2 is a rear view of the electric machine;
FIG. 3 is a left view of the electric machine;
FIG. 4 is a right view of the electric machine;
FIG. 5 is a top view of the electric machine;
FIG. 6 is a bottom view of the electric machine; and,
FIG. 7 is a front isometric view of the electric machine.

1 Claim, 6 Drawing Sheets(56)
